UNITED STATES PATENT OFFICE.

ROBERT A. CUMMINGS, OF BEAVER, PENNSYLVANIA.

CONCRETE-AND-METAL STRUCTURE.

SPECIFICATION forming part of Letters Patent No. 761,287, dated May 31, 1904.

Application filed February 14, 1903. Serial No. 143,278. (No model.)

To all whom it may concern:

Be it known that I, ROBERT A. CUMMINGS, a resident of Beaver, in the county of Beaver and State of Pennsylvania, have invented a new and useful Improvement in Concrete-and-Metal Structures; and I do hereby declare the following to be a full, clear, and exact description thereof.

My invention relates to composite metal-and-concrete structures such as are common in bridges, viaducts, docks, reservoirs, conduits, floors, roofs, walls, and other portions of fireproof buildings and other structures.

The object of my invention is to provide such a construction wherein the concrete-strengthening members serve to tie together the metal structure, thus producing a structure stronger and more rigid than those heretofore produced.

In all structures of the above-mentioned kind it is the practice to fill the spaces between metal members, whether girders, beams, columns, or the like, with concrete. The latter generally is strengthened by having a series of metal core bars or units embedded therein, which core-bars preferably are roughened or provided with projections or depressions or otherwise formed of irregular outline, so that the concrete will take a firm grip thereon, so that the core-bars prevent longitudinal expansion of the concrete, which would rupture the latter, as it has only slight tensile strength. My invention relates in general to structures of this kind; but I

improve thereupon by uniting said core bars or units at their ends to the metal members of the structure, such as the girders, beams, columns, or the like. This is preferably effected by providing the metal member with a slot and the core-bar with a flattened and broadened portion which is of such dimensions that it can be passed through the slot and when the bar is given a quarter-turn will be locked therein.

In the accompanying drawings I have shown my invention applied to a floor, ceiling, or similar horizontal structure.

In said drawings, Figure 1 is a vertical section through the structure on a plane parallel with the core-bar. Fig. 2 is a similar view

transversely of the core-bar. Fig. 3 is a plan view of the preferred form of core-bar. Fig. 4 is a cross-section thereof on line 4-4, Fig. 3. Fig. 5 is a plan view of a modified form of core-bar. Fig. 6 is a detail of another modification; and Figs. 7, 8, and 9 illustrate means for adjusting the length of the core-bar.

In the drawings the members of the metal structures are represented by the I-beam girders 1; but it will be understood that any other members of any metal structure will answer the purpose. These girders or beams are provided with metal attaching means for the core bars or units, which means may be formed in a piece separate from and attached to the beams or may be formed directly in the latter. I have shown for this purpose a series of slots 2 in the beams, which slots are of any desired shape, preferably oblong or rectangular and here shown as arranged vertically, but may be horizontal or in any other position and being of a number and distance apart depending upon the particular use for which the work is designed.

3 represents a core-bar, and 4 the concrete enveloping and embedding the same. The core-bar preferably will be such as is shown in Figs. 3 and 4, wherein is shown a round bar which is rolled, squeezed, forged, or pressed down at intervals to form the broadened flattened portions 5, which are separated by the round sections 6 of the original bar, thus producing a bar presenting a large number of shoulders which will get a good grip on the concrete, and thus greatly strengthen the latter. In lieu of this bar, however, any bar of irregular cross-section or even one which is merely roughened on the sides or even a plain bar, such as shown at 7 in Fig. 5 and at 8 in Fig. 6, may be employed. In Figs. 3, 4, 90 and 5 the bar has its end hammered, forged, or squeezed down to form a broadened flattened portion 9 of such width and thickness that when presented edgewise to the slot 2 it will pass therethrough, but which when the bar is given a quarter-turn will prevent the bar from being withdrawn from the slot, thus locking the bar and metal member 1 together. The bar shown in Fig. 6 has an oblong or lozenge-shaped head 10, which acts similar to 100

the flattened head 9 of the other type of bar. If desired, this head may be rotatably secured to the bar. While preferably the broadened flattened portion 9 of the core-bar will be at 5 the ends thereof, it is obvious that a similar locking portion may be formed at any point of the bar intermediate its ends. For instance, the particular bar shown in Fig. 3 could be locked to a beam or girder not only at its ends, 10 but also to one or more intermediate of its ends. The slots 2 in that case will be made of a width practically equal to the diameter of the circular portion 6 of the core-bar and of the height substantially the same as the 15 width of the flattened portions 5. Then said bar can be passed through the slots by simply pushing it forward and giving it quarter-turns alternately in opposite directions as it is being pushed along, thus passing the bar through the 20 slots in the three or more girders. The broadened flattened portions 9 of the bar can be readily formed at the place where the structure is being built by merely hammering the end of the bar down. Consequently very little 25 additional cost attaches to my improvement over the old structures, and, if necessary, any convenient form of bar that may be at hand can be employed, it not being necessary to use the specific bar shown in Figs. 3 and 4, although 30 I prefer either such a bar or some other bar having roughened or irregular sides in order that the concrete may take a more firm grip thereon.

In the process of manufacturing metallic structures it may happen that its members 35 are not maintained in alinement or to prescribed dimensions. It may therefore be necessary to have some arrangement whereby the length of the core-bar is adjusted. In 40 Figs. 7, 8, and 9 I have shown several arrangements suitable for this purpose. In Fig. 7 the core-bar 3 is provided with a nut 12, whereby its length is varied. If desired or necessary, the nut may be supplemented by 45 one or more ordinary washers 13. The adjustment may also be accomplished by specially-shaped washers, as shown at 13 in Fig. 8 and at 14 in Fig. 9, which represent forms 50 of washers having inclined meeting faces, so that by turning or moving them transversely on each other a variation in thickness is secured. Other adjusting means will suggest themselves to those skilled in the art.

In the use of my invention the core-bars will be locked to the metal members of the structure in the manner specified and will then be enveloped and embedded in the concrete in the well-known manner of doing this work. After the latter sets a composite metal and concrete structure is formed, which is exceedingly strong and rigid and wherein all of the members are firmly tied or locked together.

What I claim as my invention, and desire to secure by Letters Patent, is—

1. In fireproof or other structures, the combination of a core bar or unit having a series of adjacent flattened and broadened portions, a metallic member having a slot through which the core-bar is passed and wherein it is locked by means of one of its broadened and 60 flattened portions, and concrete or the like enveloping and embedding said core-bar.

2. In fireproof or other structures, the combination of a core bar or unit having a series of adjacent flattened and broadened portions, 70 girders, columns, or other metallic elements of the structure provided with slots through which the core-bar is passed and wherein it is locked by means of one of its broadened and flattened portions, and concrete or the like enveloping and embedding said core-bar.

3. In fireproof or other structures, the combination of the girders, columns, or other metallic members of the structure provided with slots, core bars or units of irregular outline 80 longitudinally having their ends broadened and flattened and passing through the slots in the metallic members and locked therein by their broadened and flattened portions, and concrete or the like enveloping and embedding 90 said core-bars.

4. In fireproof and other structures, the combination with the girders, columns or other metallic members of the structure provided with slots, of a core-bar passing through said 95 slots and provided with a head on its end, a spacing member between said head and the metallic member, and concrete or the like enveloping and embedding said core-bar.

In testimony whereof I, the said ROBERT A. 100 CUMMINGS, have hereunto set my hand.

ROBERT A. CUMMINGS.
